UNITED STATES PATENT OFFICE.

CHARLES G. DECKER, OF BROOKLYN, NEW YORK.

DESIGN FOR A SET OF PLAYING-CARDS.

52,005.

Specification for Design.

Patented May 7, 1918.

Application filed December 1, 1917. Serial No. 204,988. Term of patent 7 years.

To all whom it may concern:

Be it known that I, CHARLES G. DECKER, a citizen of the United States, residing in the borough of Brooklyn, county of Kings, and State of New York, have invented a new, original, and ornamental Design for a Set of Playing-Cards, as illustrated in the accompanying drawing.

Referring to the drawings:

Figures 1, 2, 3, 4, 5, 6 and 7, are front

views and Fig. 8 is a back view of certain cards of the set.

What I claim is:

The ornamental design for a set of playing cards, as shown.

CHARLES G. DECKER.

Witnesses:

F. GRAVES,

CHARLES M. DEAN.
